(57) **CLAIM**

The ornamental design for a retractable boat hammock set, as shown and described.

DESCRIPTION

FIG. 1 is a perspective view of a retractable boat hammock set in a retracted position;

FIG. 2 is a top view of the retractable boat hammock set in the retracted position;

FIG. 3 is a left side view of the retractable boat hammock set in the retracted position;

FIG. 4 is a right side view of the retractable boat hammock set in the retracted position;

FIG. 5 is a perspective view of a retractable boat hammock set in an extended position;

FIG. 6 is a left side view of the retractable boat hammock set in the extended position;

FIG. 7 is a right side view of the retractable boat hammock set in the extended position; and,

FIG. 8 is a top view of the retractable boat hammock set in the extended position.

The broken lines in the drawings depict the environmental structure of the retractable boat hammock set that form no part of the claimed design.
